CARRIER FOR PNEUMATIC DISPATCH TUBE APPARATUS

John T. Needham, North Plainfield, N. J., assignor to Lamson General Conveyors, Limited, Montreal, Quebec, Canada, a corporation of Canada

Application September 23, 1935, Serial No. 41,642

18 Claims. (Cl. 243—34)

An important object of the present invention is to provide an improved carrier so designed as to facilitate its manufacture at a low cost.

Other objects of the invention will appear hereinafter.

In the drawings:

Fig. 1 is a central longitudinal view of the carrier with the two shells arranged in open position;

Fig. 2 a transverse sectional view of one head of the carrier taken on the line 2—2 of Fig. 1;

Fig. 3 a transverse sectional view of the carrier body taken on the line 3—3 of Fig. 1;

Fig. 4 a detail transverse sectional view of a portion of one head of the carrier taken on the line 4—4 of Fig. 1;

Fig. 5 a detail view of a portion of the accelerating washer carried by the head of the outer shell;

Fig. 6 a side elevation of the inner shell partly formed, a part being broken away;

Fig. 7 a view similar to Fig. 6 of the outer shell;

Fig. 8 a detail side elevation partly in section of the metal cup which is secured to and closes the outer end of the inner shell;

Fig. 9 a view similar to Fig. 8 of the cup which is secured to and closes the outer end of the outer shell;

Fig. 10 a side elevation of the lock hinge by means of which the two shells are rotatively locked together;

Fig. 11 a view of the blank from which the inner cylindrical shell is formed;

Fig. 12 a view of the blank from which the outer shell is formed;

Fig. 13 a detail view of the felt disk from which the felt covering for the heads is formed; and

Fig. 14 a detail view of a pair of dies for shaping the felt disk to fit the carrier heads.

The carrier comprises a tubular cylindrical outer shell 1 and a similar inner shell 2 closely fitted in the outer shell, the two shells when interfitted forming a tubular cylindrical container body. The shells are made of sheet metal, preferably steel of the desired thickness.

The inner shell 2 is formed from a flat blank 3 cut out along its longitudinal edges as at 4 to form the large entrance aperture 5 in the finished shell, as shown in Figs. 1 and 3. The margins of these cut out portions are folded outwardly to form the flanges 6 around the entrance aperture as indicated in Figs. 1 and 3. By folding the marginal edges of the cut out portions, as described, the entrance aperture is provided with a smooth finishing welt around its edge. At one end of the blank 3 a series of longitudinally extending prongs 7 are formed, said series of prongs extending along the entire edge of the blank and

being spaced suitable distances apart. A short distance inwardly from prongs 7 is formed a series of stamped out tongues 8. These tongues 8 are arranged across the entire width of the blank and a short distance inwardly from the prongs 7 and extend in a direction opposite the prongs 7, that is to say the free ends of the tongues 8 are inward of the end of the blank.

The blank 3 is bent by suitable means into cylindrical form and the abutting edges 9 and 10 are temporarily or permanently connected together to hold the shell to form. The end of the cylindrical shell opposite the prongs 7 is then slightly reduced in diameter as at 11 by a suitable operation. The end of this reduced portion 10 is then bent to form the flange 12, said flange being turned outwardly, and compressed against a ring 13, said ring serving to rigidly hold the shell in cylindrical form. The reduction in diameter of the shell to form the reduced portion 11 results in the formation of an internal shoulder or abutment 11a. The formation of the annular flange 12 at the end of the shell 2 results in an internal abutment or shoulder 12a. These internal abutments 11a and 12a cooperate with the means for retaining the two shells in assembled position, as will be more fully hereinafter described.

In the reduced portion 11 at the inner end of the shell 2, outwardly pressed abutments 21 and 21a are formed at diametrically opposite points. The abutment 21 is adapted to cooperate with inwardly pressed abutments formed on the outer shell, as will be hereinafter described. The inner sides of the abutments 21 and 21a form inwardly facing pockets 21b which are adapted to receive the spring locking means to lock the two shells in closed position, as will be hereinafter described.

The body of the shell is slightly reduced in diameter by a suitable operation to form a slight shoulder 14 close to the free ends of the tongues 8. The free ends of the tongues 8 are bent outwardly, as shown clearly in Fig. 6, so that the said tongues incline with respect to the axis of the shell. The prongs 7 are on that end of the blank 45 which forms the outer end of the finished shell. To close the outer end of the shell 2 a sheet metal end cup 15 is provided. This cup is formed of a sheet metal stamping and comprises the central well 16, considerably smaller in diameter than the body of the shell, and the circular portion 17 formed with an annular flange 18 around the edge thereof, said flange and the annular wall of the well 16 extending from the same side of the annular portion 17 and in the same direction. The portion 17 is formed with an annular series of apertures 19 which are adapted to receive the prongs 7 on the end of the shell. Inwardly of the apertures 19 a series of tongues 20 are stamped out of the portion 17, 60

said tongues extending outwardly from the cup margin at an angle with respect to the axis of the cup. The prongs 7 after passing through the apertures 19 are bent over and firmly clinched to the outer side of the flange 18, as shown clearly in Fig. 1.

The cup 15 serves to close the outer end of the shell 2 and to form the end wall thereof, the well 16 forming an inwardly extending depression in said end wall. The cup also reinforces the shell and ensures it remaining in its cylindrical form. The ring 13 reinforces the inner end of the shell 2 and ensures the inner end of the finished shell remaining in true cylindrical form.

The outer shell 1 is formed from a flat blank 22 cut out along its longitudinal edges as at 23 to form the large entrance aperture 24 in the finished shell, as shown in Figs. 1 and 3. The margins of these cut out portions are folded inwardly to form the flanges 25 around the entrance apertures, as shown in Figs. 1 and 3. By folding the marginal edges of the cut out portions, as described, the entrance aperture is provided with a smooth finishing welt around its edge. The entrance aperture in the outer shell is of such dimensions and is so located in the shell that when the inner and outer shells are placed in position to fully open the entrance aperture the margin of the aperture 25 extends slightly beyond the margin of the aperture 5 of the inner shell except at the extreme ends of the apertures where the margins coincide, as shown in Figs. 1 and 3. The entrance apertures in both shells are approximately of the same dimensions. This permits of the maximum dimensions of the entrance aperture with the removal of the least amount of metal from the outer shell. This is of advantage in that the outer shell is thereby made slightly stronger and in the fully opened positions of the two shells the margin of its aperture extends beyond the margin of the aperture of the inner shell, except at the ends of the apertures, and thereby to a certain extent protects the inner shell.

The blank 22, at one end, is formed with a series of longitudinally extending prongs 26, said series of prongs extending along the entire edge of the blank and being spaced suitable distances apart. A short distance inwardly from the prongs 26 is formed a series of stamped out tongues 27. These tongues 27 are arranged across the entire width of the blank and a short distance inwardly from the prongs 26 and extend in a direction opposite to the prongs 26, that is to say the free ends of the tongues 27 are inward of the end of the blank.

The blank 22 is bent by suitable means into cylindrical form and the abutting edges 28 and 29 are temporarily or permanently connected together to hold the shell in its cylindrical form. The end of the cylindrical shell, opposite the prongs 26, is forced outwardly to form the outwardly extending annular flange 30, said flange being located at the inner open end of the shell. The tongues 27 are forced outwardly to a position at an angle with respect to the axis of the shell as shown clearly in Fig. 7. A slight distance inwardly of the tongues 27 an annular outwardly extending flange 31 is formed in the body of the shell 1. Inwardly pressed abutments 32 and 32^a are formed in the body of the shell adjacent the tongues 27 and at properly spaced points around the shell, as shown in Figs. 2 and 7. These abutments 32 and 32^a coop-

erate with abutment 21 on the inner shell to serve as limiting stops for the rotation of the shells on each other, abutment 32 stopping the shells in open position, as shown in Figs. 1 and 2, and abutment 32^a stopping the shells in closed position.

To close the outer end of the shell 1 an end cup 33 is provided. This cup is formed of a sheet metal stamping and comprises the central well 34 considerably smaller in diameter than the body of the shell and the circular portion 35 formed with an annular flange 36 around the edge thereof, said flange and the annular wall of the well 34 extending from the same side of the circular portion 35 and in the same direction. The portion 35 is formed with an annular series of apertures 37 which are adapted to receive the prongs 26 on the end of the shell 1. Inwardly of the apertures 37 a series of tongues 38 are stamped out of the portion 35, said tongues extending outwardly from the cup margin at an angle with respect to the axis of the cup. The prongs 26, after passing through the apertures 37, are bent over and firmly clinched to the outer side of the flange 36, as shown clearly in Fig. 1.

Around the flange 30 at the inner end of the outer shell is secured an annular clamping flange 39. This clamping flange reinforces the inner end of the shell 1 and serves to hold the shell 30 in cylindrical form. The cup 33 closes the outer end of the shell 1, and forms the end wall of the finished shell, the well 34 forming an inwardly extending depression in said end wall open to the exterior of the carrier. The cup also reinforces the shell and ensures its outer end remaining in cylindrical form.

The annular wall of the well 34 is provided with two apertures 40 at diametrically opposite points to receive the ends of a retaining spring, 40 and the said wall is also formed with an aperture 40^a to receive medial portion of the said retaining spring, as will be more fully hereinafter described. The said wall is also formed with an aperture 40^b which serves to give access to a portion of a locking spring, which spring serves to lock the two shells in open position, as will be more fully hereinafter described.

When the two shells are assembled the well portion 34 of the cup 33 extends into the inner shell through the end opening formed by the flange 12, the said well portion being approximately of the same diameter as the said opening, as shown clearly in Fig. 1, and the flange 39 on the inner end of the outer shell is only a slight distance from the shoulder 14 at the outer end of the inner shell. The reduced portion 11 of the inner shell and the annular wall of the well 34 form an annular clearance space to receive the means for yieldably locking the shells in their closed position, and also the means for retaining the two shells in assembled position against endwise displacement. To hold the two shells together and to permit of the rotation of said shells to open and closed positions a retaining ring 41 is provided. The internal diameter of this ring is such that it fits around and receives within it the annular wall of the well 34 of the cup 33. The ring 41 is provided with an annular flange 43 slightly larger in diameter than the flange 42, the outer marginal edge of the flange 43 resting on the internal abutment 11^a of the inner shell. The inner surface of the flange 43 is flush, or substantially so, with the inner surface of the transverse wall of the well 34, 75

and said flange serves as a cover or closure for the annular clearance space or chamber formed by the wall of the reduced portion 11 of the inner shell and the annular wall of the well 34.

The retaining ring 41 is detachably connected to the annular wall of the well 34 and thereby serves to detachably retain the two shells in assembled position. The means for detachably securing the retaining ring to the cup of the outer shell comprises a retaining spring 44. This spring is arranged in the well 34 so that it may be inserted and removed through the cup 33 and is always accessible from the exterior of the carrier. The ends of this retaining spring are bent outwardly to form the retaining fingers 45 which extend radially outwardly as shown in Fig. 2. These retaining fingers extend through the apertures 40 in the annular wall of the well 34 and also extend outwardly through apertures 46 in the retaining ring 41. The spring 44, midway its ends is bent outwardly to form a loop 47 which extends radially outwardly through the apertures 40^a in the annular wall of the well 34 and through an aperture 48 in the ring 41. The retaining spring 44 therefore connects the cup 33 to the ring 41 and said ring is free to rotate with the outer shell. The flange 42 resting on the abutment 12^a holds the two shells together against endwise separating movement. The flange 43 assists in retaining the shells against endwise separating movement by engaging the shoulder or abutment 11^a and also serves to close the annular clearance chamber, as hereinbefore described, and prevents the contents of the carrier becoming caught or jammed in said chamber. It also covers and protects the retaining spring.

Whenever it is desired to separate the two shells the retaining spring 44 is manipulated by any suitable means inserted into the well 34 of the cup 33 to withdraw the retaining fingers from the apertures 40 and 46. The spring loop 47 may then be withdrawn from apertures 40^a and 48.

To lock the shells in their closed position a locking spring 49 is arranged in the channel formed by the flanges 42 and 43 of the ring 41. This locking spring is provided with an inwardly extending loop 50 midway its ends, said loop extending through a flanged aperture 51 in the ring 41 and also through the aperture 40^b of the annular wall of the well 34 so that said loop also serves as a supplementary means for locking the retaining ring 41 to the cup 33 of the outer shell. The ends of the locking spring 49 are bowed outwardly to form the outwardly curved locking detents 52. The arms of the spring 49 between the loop 50 and the locking detents 52 tend to spring outwardly and to maintain the locking detents against the inner surface of the reduced portion 11 of the inner shell, as shown clearly in Fig. 2. The locking spring with its detents 52 is so placed with respect to the locking sockets 21^b of the inner shell that when the abutment 21 engages the abutment 32^a the detents 52 will snap into said socket 21^b and hold the two shells locked in closed position. A slight pressure on the shells tending to rotate them to open position will force the spring detents 52 out of the sockets 21^b and permits the shells to be rotated to open position.

When it is desired to separate the two shells and the retaining spring 44 has been removed, it is necessary to force the loop 50 outwardly a sufficient distance to free it from the annular wall of the well 34. This may readily be done

because the loop 50 is accessible from the exterior of the carrier through the open end of the well 34, as shown clearly in Fig. 1. One shell may then be withdrawn endwise from the other. The locking spring 49 serves to lock the two shells in closed position. It does not lock the two shells in open position, as is clearly shown in Fig. 2 of the drawings.

When assembling the two shells the loop 50 of the locking spring must be brought into register with the aperture 40^b of the cup 33. This will bring into register apertures 40 and 46 and apertures 40^a and 48. The loop 47 of the retaining spring 44 may then be passed outwardly through the registering apertures 40^a and 48, and the retaining fingers 45 of said spring may be passed through the registering apertures 40 and 46. The aperture 40^b of the cup 33 is so located with respect to the abutments 32 and 32^a of the outer shell 1, that when the loop 50 of the locking spring extends into aperture 40^b the spring detents 52 will be so located that when the abutment 21 of the inner shell engages the abutment 32^a of the outer shell, the spring detents will snap into the locking sockets 21^b of the inner shell.

Buffer heads are secured to the outer ends of both the inner and outer shells. These heads are of the same construction and therefore a description of one will be sufficient. Under the tongues 8 of the inner shell is placed an annular band or ring of rubber 54. This ring is inclined on its outer surface to fit snugly under the tongues 8. Under the tongues 20 is arranged an annular band or ring 55 of rubber, said band being inclined on its outer face to conform to the inclination of the tongues 20 and to fit snugly between said lugs and the portion 17 of the cup 15. The rubber bands 54 and 55 are suitably secured in position by cement, or by vulcanization or otherwise. Surrounding and enclosing the outer end of the carrier and fitting closely over the tongues 8 and 20 is a re-inforcing buffer head portion 56 of rubber. This buffer head portion is substantially right angular in cross section with the outer surface thereof rounded, as shown clearly in Fig. 1. This head portion 56 is a ring-like structure having an opening of substantially the same diameter as the internal diameter of the well portion of the end cup to which it is secured. This head portion 56 is preferably molded to form and is then cemented or vulcanized or otherwise secured in position. The rubber rings 54 and 55 are intimately united with the head portion 56 between the tongues by cement or vulcanization or otherwise so that the head portion 56 is securely anchored to the tongues 8 and 20, and to the exterior of the shell.

The outer surface of the head 56 is preferably enclosed within a felt covering 57. This felt covering is preferably made from a ring 58 of sheet felt of the desired thickness. The ring 58 is saturated with water and is then placed between two dies and pressed to the proper form to accurately fit the rounded exterior surface of the head portion 56. In Fig. 14 is illustrated a pair of dies suitable for pressing the ring 58 to proper form. When the pressed ring has dried it is permanently in shape to be fitted to the surface of the head 56 and may be secured thereto by cement, vulcanization or otherwise. As shown in Fig. 1 access may be had to the interior of the wells of the end cups through the central opening in the head 56 and the felt covering ring 57.

An accelerating washer 59 of rubber, or other suitable flexible material, is permanently se-

cured to the flat transverse edge of the head portion 56 of the inner shell, and said washer is held in place by means of a metal ring 60 secured to the inner face of said washer and between which and the head the washer is permanently held. The washer 59 lies in a plane transverse to the axis of the shell. When the two shells are assembled the finished flange 39 of the outer shell contacts slightly with the metal washer 68; as shown clearly in Fig. 1.

A removable accelerating washer 61 is secured to the transverse flat edge of the head portion 56 of the outer shell. This washer 61 is formed of a ring of comparatively stiff but flexible material which is cut out around its inner margin as at 62 to reduce the stiffness of the material and to permit it to be expanded sufficiently to pass over the flanges 39 and 31 of the outer shell. Secured to the flat sides of the ring 61 are two comparatively soft flexible rubber rings 63, said rings covering the cut-out portions 62. The rings 63 are sufficiently flexible to permit the composite ring to be expanded sufficiently to pass over the flanges 39 and 31. The composite washer 61—63 fits between the flange 31 and the adjacent flat face of the head portion 56 and lies in a plane transverse of the axis of the shell. The washer 61 may be readily removed when it becomes worn and a new washer placed in position on the head of the outer shell. If desired the ring 63 contacting with the head portion 56 may be cemented or otherwise secured thereto.

From the foregoing it is manifest that all the metal parts of the carrier may be made of stamped sheet metal and that these parts may be readily stamped or otherwise shaped to final form. The parts forming the buffer heads may be readily molded in proper form and then cemented or otherwise secured to the carrier shell. The result of such construction is that the carrier may be cheaply and quickly made, and will be of sturdy construction to withstand the rough usage to which carriers of this type are subjected in use.

What I claim is:

1. A carrier comprising a pair of tubular shells fitted one within the other and each having an entrance opening in its side, said shells being relatively rotated to bring said openings into and out of register with each other to open and close the carrier, characterized in that the inner shell has an inwardly extending annular transverse abutment at its inner end, a retaining ring within the inner shell and in engagement with the said annular flange, and releasable retaining means extending through the outer shell and engaging the retaining ring to hold the two shells against endwise displacement, said releasable retaining means being accessible from the exterior of the carrier.

2. A carrier comprising a pair of tubular shells fitted one within the other and each having an entrance opening in its side, said shells being relatively rotatable to bring said openings into and out of register with each other to open and close the carrier, characterized in that a retaining ring is within the inner shell and in engagement with a cooperating part of the inner shell, and releasable retaining means extends through the outer shell and engages the retaining ring to hold the retaining ring and the two shells against endwise displacement, said releasable retaining means being accessible from the exterior of the carrier.

3. A carrier comprising a pair of tubular shells

fitted one within the other and each having an entrance opening in its side, said shells being relatively rotatable to bring said openings into and out of register with each other to open and close the carrier, characterized in that the outer shell has an end wall centrally depressed inwardly to provide it with an annular wall portion, and the adjacent end portion of the inner shell is peripherally contracted to provide the shell with a transverse, annular internal shoulder and with an annular wall concentric with and spaced from said annular portion of the end wall, and a shell-retaining ring is interposed between said annular walls and has a flange bearing against said internal shoulder of the inner shell for the purpose set forth, and said ring and the annular portion of the end wall have registering apertures, and means extend through said aperture to hold the retaining ring and the inner shell to the outer shell against endwise displacement, and said holding means are shiftable to release position from the exterior of the carrier through said end depression.

4. A carrier according to claim 3, characterized in that said holding means comprises a bowed retaining spring arranged in the end depression and having a medial locking projection extending through said apertures to lock the retaining ring in the outer shell to thereby hold the retaining ring and the inner shell to the outer shell against endwise displacement, said retaining spring being shiftable to release position from the exterior of the carrier through said end depression.

5. A carrier comprising a pair of tubular shells fitted one within the other and each having an entrance opening in its side, said shells being relatively rotatable to bring said openings into and out of register to open and close the carrier, characterized in that said shells have a clearance space therebetween at one point in their length and extending around their axis of rotation, and the inner shell is pressed outward at one point on its periphery to form a recess and to form a stop projection in said clearance space, and the outer shell is pressed inward at one point on its periphery to form an integral stop projection in said space cooperable with said first projection to limit relative rotation of the shells, and yieldable snap locking means are provided to engage in said recess to yieldably resist relative rotation of the shells in a direction to separate said stops.

6. A carrier comprising a pair of tubular shells fitted one within the other and each having an entrance opening in its side, said shells being relatively rotatable to bring said openings into and out of register to open and close the carrier, characterized in that the shells have a clearance space therebetween at a point adjacent one end of the carrier and extending around their axis of rotation, and the inner shell is pressed outwardly at two diametrically opposite points on its periphery to form inwardly facing recesses and outwardly extending stop abutments in said clearance space, and the outer shell is pressed inwardly at one point on its periphery to form an inwardly extending stop abutment projecting into said space and cooperable with one of the abutments on the inner shell to limit relative rotation of the shells to closed position, and two yieldable snap locking detents are provided in said clearance space and connected to the outer shell, said detents being arranged to snap into the inwardly facing recesses in the inner shell to yieldably resist relative rotation of the shells in a

direction to separate said stop abutments to open the carrier.

7. A carrier comprising a pair of tubular shells fitted one within the other and each having an entrance opening in its side, said shells being relatively rotatable to bring said openings into and out of register to open and close the carrier, characterized in that the shells have a clearance space therebetween at a point adjacent one end of the carrier and extending around their axis of rotation, and the inner shell is pressed outwardly at two diametrically opposite points on its periphery to form inwardly facing recesses and outwardly extending stop abutments in said clearance space, and the outer shell is pressed inwardly at one point on its periphery to form an inwardly extending stop abutment projecting into said space and cooperable with one of the abutments on the inner shell to limit relative rotation of the shells to closed position, and a retaining ring is arranged in said clearance space and in engagement with the inner shell, and two yieldable snap locking detents are provided in said clearance space and releasably connected to the outer shell and the retaining ring to lock the two shells against end-wise displacement, and said detents being arranged to snap into the two inwardly facing recesses in the inner shell to yieldably resist relative rotation of the shells in a direction to separate said stop abutments and to open the carrier.

8. A carrier according to claim 3, characterized in that said holding means comprises a bowed retaining spring arranged in said end depression, the spring has a medial locking projection extending through said apertures to lock the retaining ring in the outer shell to thereby hold the retaining ring and the inner shell to the outer shell against endwise displacement, said spring also has retaining fingers extending approximately radially of the carrier, the annular wall of said depression and the annular wall of the retaining ring have registering apertures into which said fingers snap, and said retaining spring is shiftable to release position from the exterior of the carrier at said depression.

9. A carrier comprising a pair of tubular shells fitted one within the other and each having an entrance opening in its side, said shells being relatively rotatable to bring said openings into and out of register with each other to open and close the carrier, characterized in that said shells have a clearance space therebetween at a point in their length and extending around their axis of rotation, a retaining abutment element is disposed in said space, one of the shells has an abutment to engage said abutment element, a fastening element extends through the other shell and releasably engages said abutment element to hold it in place, said abutment element, said shell abutment and said fastening element are constructed and arranged to cooperate to hold together the shells against relative endwise displacement, and the fastening element is accessible from the exterior of the carrier for release of said element to permit separation of the shells.

10. A carrier according to claim 9, characterized in that the carrier parts are constructed and arranged to permit endwise withdrawal of the inner shell and the said retaining abutment element from the outer shell upon release of said fastening means.

11. A carrier comprising a pair of tubular shells fitted one within the other and each having an entrance opening in its side, said shells being rela-

tively rotatable to bring said openings into and out of register with each other to open and close the carrier, characterized in that the outer shell has an outer end wall formed with a depressed portion forming a recess opening outside of the carrier and a protuberance within the carrier and having a space around its periphery within the carrier, a retaining abutment element is disposed in said space, an abutment is borne by the inner shell within the carrier and is engageable by said abutment element, a fastening means penetrates said depressed end wall portion and releasably engages said abutment element to hold it in place, said abutment element, said inner shell abutment and said fastening means cooperate to hold the shells together against relative endwise displacement, and said fastening means is accessible for release thereof at said end recess for separation of the shells.

12. A carrier according to claim 11, characterized in that said retaining abutment element is annular in shape and surrounds the said inward protuberance of the end wall of the outer shell and is substantially flush with said protuberance to form therewith a substantially continuous end wall for the containing space of the carrier.

13. A carrier according to claim 11, characterized in that said retaining abutment element is in the form of a ring surrounding the said inward protuberance of the end wall of the outer shell, the adjacent end portion of the inner shell is reduced in diameter to afford between the inner and outer shells a space extending around their axis of rotation, and the shells have stops within said space to limit relative rotation of the shells.

14. A carrier according to claim 11, characterized in that the end portion of the inner shell adjacent to said depressed end wall of the outer shell is reduced in diameter to afford a space between the shells extending around their axis of rotation, the shells have stops within said space to limit relative rotation of the shells, and the said releasable fastening means embodies resilient locking means cooperable with the inner shell for yieldable snap locking of the shells in closed relation.

15. A carrier according to claim 11, characterized in that the said releasable fastening means embodies resilient locking means cooperable with the inner shell for yieldable snap locking of the shells in closed relation.

16. A carrier according to claim 11, characterized in that the said releasable fastening means comprises a resilient element normally held by its resilience in retaining engagement with the said retaining abutment element and adapted to be forcibly retracted from the abutment element for release of the latter and separation of the shells.

17. A carrier according to claim 11, characterized in that the carrier parts are constructed and arranged to permit endwise withdrawal of the inner shell and the said retaining abutment element from the outer shell in a direction away from said end wall of the outer shell upon release of said fastening means.

18. A carrier according to claim 11, characterized in that the said end of the outer shell bears an annular buffer head whose central aperture is in register with the said end recess of the shell for entry to the recess to release the said fastening means, and said buffer head is secured to the outer shell independently of the inner shell.
